(57) **CLAIM**

The ornamental design for an optical fiber coating removal tool as shown and described.

DESCRIPTION

FIG. 1 is a front view of an optical fiber coating removal tool of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front perspective view thereof;

FIG. 8 is a rear perspective view thereof; and,

FIG. 9 is a sectional view taken along the line 9-9 of FIG. 1.

The broken lines show portions of an optical fiber coating removal tool that form no part of the claimed design.

The alternate long and short dash lines are merely the boundary lines between the claimed parts and the non-claimed parts.
